UNITED STATES PATENT OFFICE.

GEORGE L. COLLEDGE, OF CANTON, OHIO, ASSIGNOR OF ONE-HALF TO
CHARLES A. VAN DUSEN, OF CANTON, OHIO.

AIR-BRAKE.

SPECIFICATION forming part of Letters Patent No. 689,576, dated December 24, 1901.

Application filed May 24, 1901. Serial No. 61,677. (No model.)

To all whom it may concern:
Be it known that I, GEORGE L. COLLEDGE, a citizen of the United States, residing at Canton, in the county of Stark and State of Ohio, 5 have invented certain new and useful Improvements in Air-Brakes; and I do hereby declare that the following is a full, clear, and exact description of the same, reference being had to the annexed drawing, making a 10 part of this specification, and to the figures of reference marked thereon, in which the drawing illustrates a sectional view showing the different parts properly arranged and illustrating my improvement.

15 The present invention has relation to air-brakes; and it consists in the peculiar construction hereinafter described.

The object and purpose of the present invention is to provide means by which the auxiliary reservoirs can be recharged simultaneously with the train-line. This object is brought about by the construction hereinafter described.

In the accompanying drawing, 1 represents 25 the train-line connection, which is provided with the ordinary screen 2, which is connected in the ordinary manner. The chamber 3 is of the ordinary construction and forms no particular part of the present invention, except 30 that such a chamber must necessarily be used or one substantially like it. From the chamber 3 leads the main passage 4 to the chamber 5, said chamber 5 being provided with the port or ports 6. In the drawing I 35 have illustrated two ports; but it will be understood that the number may be increased or decreased without departing from the nature of my invention, as the only object of the port 6 is to provide a means for allowing 40 air to enter the triple-valve-piston chamber 7, said air when forced into the chamber 7 bringing the piston 8 to release position shown in the drawing.

The parts above referred to are those of 45 common construction and form no particular part of the present invention except as they are used with my improved construction.

From the chamber 7 leads the recharge-port 50 9, which recharge-port leads and communicates with the chamber 10, and when pres-

sure is brought to bear against the piston 11 it is driven against the equalizing-spring 12, which spring is located around the stem 13, which stem extends upon either side of the piston 11, as illustrated in the drawing. When 55 the piston 11 is driven away from the recharge-port 9, it carries with it the stem 13, at which time the port 14 is opened by reason of the longitudinal movement of the stem 13, said movement opening the valve 15 and 60 allowing the air to pass through port 16 from chamber 10 into the slide-valve chamber 17, thereby filling the auxiliary reservoir. At the same time air passes from the slide-valve chamber 17 through port 18 into chamber 65 19, thereby equalizing the pressure in chambers 19 and 10 and train-line and auxiliary reservoir, and when the pressure is equal in all of the above-mentioned chambers and train-line the spring 12 forces the piston 11 70 toward the recharge-port 9, thereby closing the port 14.

When a train-line reduction is made to apply the brakes, the brake-valve piston 8 moves against the graduating-stem 20, thereby 75 closing the recharge-port 9, making the piston 11 inoperative until the brakes are again released, which moves the piston 8 back to the position illustrated in the drawing.

Heretofore the periphery of the chamber 7 80 was provided with very small feeding-ports, and they must under the old construction be small, owing to the fact the air would escape; but by my peculiar arrangement I do away with the feed-ports located in the periphery 85 of the chamber 7 and provide one recharge-port 9, thereby allowing a rapid recharge.

Heretofore and with the old feed-ports it was impossible to recharge auxiliary reservoirs to their full capacity (which is about 90 seventy pounds) in much less than two minutes; but with my peculiar arrangement and by the increased size of the recharge-ports 9, 14, and 16 I am enabled to recharge after a reduction has been made as fast as train-line can be recharged from the main reservoir, which is almost instantaneously—is, in fact, instantaneously for all practical purposes.

It will be understood that my improved de- 100

vice can be connected different from the exact construction shown and the same object accomplished--as, for instance, in the drawing the recharge-ports and valve are shown on top of the triple valve; but, it will be understood, it may be located to one side, if desired.

The end of the cylinder 19 is closed by the cap-nut 21, which cap-nut is provided with the recesses 22, said recesses being for the purpose of holding the spring 12 and also act as a guide for the stem 13.

It will be understood that the different parts of the air-brake proper are constructed in the ordinary manner, reference being had to connecting my improvement thereto, said parts being shown only for the purpose of illustrating my application and need no description here.

Having fully described my invention, what I claim as new, and desire to secure by Letters Patent, is—

1. In an air-brake the combination of a cylinder or chamber having located therein a brake-valve piston, a recharge-port leading from said cylinder or chamber into and communicating with a chamber having located therein a piston, said piston forming a division in said chamber and fixed to a stem, a port controlled by the piston-stem and a port leading from the chamber having the port controlled by the piston-stem into the sliding-valve chamber 17 and a spring located around the piston-stem upon the opposite side of the

piston from that controlling the port, substantially as and for the purpose specified. 35

2. In an air-brake the combination of a brake-operating piston located in a cylinder, a cylinder spaced from the cylinder containing the brake-operating piston, and having located in said cylinder a piston, said piston forming a partition in the chamber in which it is located, a recharge-port located between the brake-operating-piston cylinder and the spaced chamber, ports located upon opposite 45 sides of partition-piston and leading to the slide-valve chamber, the partition-piston provided with stems upon its sides, and one of the ports controlled by one of the piston-stems, substantially as and for the purpose 50 set forth.

3. In an air-brake, a brake-piston located in a cylinder, a recharge-port leading from said cylinder to an air-chamber having located therein a piston, said piston forming a partition for the chamber in which it is located, and ports leading from said air-chamber to the slide-valve chamber upon opposite sides of the piston, one of said ports controlled by the stem of the piston, substantially as and for 60 the purpose specified. 55

In testimony that I claim the above I have hereunto subscribed my name in the presence of two witnesses.

GEORGE L. COLLEDGE.
